(57) **CLAIM**

The ornamental design for an internal-combustion engine, as shown and described.

DESCRIPTION

FIG. 1 is a first perspective view of an internal-combustion engine;

FIG. 2 is a second perspective view of the internal-combustion engine;

FIG. 3 is a front elevation view of the internal-combustion engine;

FIG. 4 is a rear elevation view of the internal-combustion engine;

FIG. 5 is a top plan view of the internal-combustion engine;

FIG. 6 is a bottom plan view of the internal-combustion engine;

FIG. 7 is a right side elevation view of the internal-combustion engine; and,

FIG. 8 is a left side elevation view of the internal-combustion engine.

The broken lines shown in the drawings are for the purpose of illustrating portions of the article that form no part of the claimed design.

1 Claim, 8 Drawing Sheets
